BRAKE SHOE KEY

Frederic Schaefer, Pittsburgh, Pa.

Application November 9, 1935, Serial No. 49,069

8 Claims. (Cl. 188—243)

This invention relates to keys for connecting railway brake shoes to brake heads, and has among its objects the provision of a brake key which may be quickly and positively locked in position, which can not accidentally become unlocked in service, which is easily unlocked when desired, and which is simple, durable and inexpensive in construction.

The preferred embodiment of the invention is illustrated in the accompanying drawing in which Fig. 1 is a side view of the key inserted through the cooperating lugs of a brake head and shoe but not locked therein; Fig. 2 is a view similar to Fig. 1 showing the key locked in place; Fig. 3 is a face view of the key looking at it from the left as seen in Fig. 2; and Fig. 4 is a view of the opposite face of the key.

Referring to Fig. 1 of the drawing, a brake shoe 1 having a central lug 2 is shown associated with a brake head 3 provided with a pair of lugs 4 straddling lug 2. All of these parts are of standard construction. The brake shoe is connected to the brake head by a key extending through the cooperating lugs and comprising a pair of arms 6 and 7, preferably resilient, slidably connected together at their opposite ends to permit arm 7 to be moved longitudinally of arm 6. Thus, the lower end of arm 6 is shown as being offset toward the brake shoe with the connecting portion of the arm provided with a slot 8 in which a tongue 9 formed on the lower end of arm 7 is slidably disposed. The upper end portion 11 of arm 6 is bent over the top of the brake shoe to limit downward movement of the key relative thereto, and a slot 12 is formed in portion 11 by cutting a tongue 13 in the arm and bending it back as shown. A tongue 14 formed on the upper end of arm 7 is slidably disposed in slot 12, and to provide for moving arm 7 longitudinally relative to arm 6 the upper end of this tongue is coiled around a pin 16 traversing a recess in a latch 17 having the general form of a bell crank lever. When the long arm of the latch extends upwardly, as shown in Fig. 1, arm 7 is in its lowest position relative to arm 6, but when the long arm of the latch is swung toward the brake head arm 7 is raised thereby relative to the opposite arm as shown in Figs. 2, 3, and 4. In this position the long arm of the latch rests on tongue 13.

It is a feature of this invention that the key is locked in position when arm 7 is raised relative to arm 6 in the manner just described. Accordingly, upward movement of arm 7 causes a dent or boss 18 on the inner face of that arm to ride up the inclined upper wall of a depression 19

formed in the adjoining arm, and to thereby spread the two arms apart and into firm engagement with lugs 2 and 4 as shown in Fig. 2. While the arms are in this position the key can not be removed from the lugs because arm 7 is provided with a detent 21 projecting from its outer face below upper lug 4 past which the detent can not move. To positively maintain the arms spread apart below detent 21, arm 6 also is preferably provided with a detent 22 that engages the inner face of arm 7 (Fig. 2).

When latch 17 is swung upwardly and toward the brake shoe to lower arm 7, boss 18 is received in depression 19 and detent 22 is received in the depression formed by detent 21, whereby the arms are permitted to collapse into engagement with each other throughout the major portion of their length as shown in Fig. 1. This leaves sufficient clearance between the key and lugs to allow detent 21 to pass upper lug 4 so that the key can be withdrawn from the lugs to permit the brake shoe to be removed from the head. The upper portion of tongue 13, besides forming a support for the latch, is also used in driving the key into and out of position.

A brake key constituted in accordance with this invention is simple and durable in construction, but can be positively locked in position by merely swinging the latch downwardly toward the brake head. Furthermore, although the key can not become accidentally unlocked in service and permit the brake shoe to drop, it can be readily unlocked when desired by merely raising the latch.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A key for connecting a brake shoe to a brake head, comprising a pair of adjoining overlapping arms connected to each other for relative longitudinal movement, means for spreading said arms apart and into shoe-locking position when subjected to said movement, and means for effecting said longitudinal movement to spread said arms.

2. A key for connecting a brake shoe to a brake head, comprising a pair of adjoining overlapping arms slidably connected to each other for relative longitudinal movement, means integral with

said arms for spreading said arms apart and into shoe-locking position when subjected to said movement, and means for effecting said longitudinal movement to spread said arms.

- 5 3. A key for connecting a brake shoe to a brake head having cooperating lugs, comprising a pair of adjoining overlapping arms slidably connected to each other for relative longitudinal movement and provided with a lug-engaging detent and means for spreading said arms apart and into shoe-locking position when subjected to said movement, and means for effecting said longitudinal movement to spread said arms.
- 10 4. A key for connecting a brake shoe to a brake head, comprising a pair of adjoining overlapping arms slidably connected to each other at one end for relative longitudinal movement, means for spreading said arms apart and into shoe-locking position when subjected to said movement, and means for effecting said longitudinal movement to spread said arms.

- 15 5. A key for connecting a brake shoe to a brake head, comprising a pair of adjoining overlapping arms slidably connected to each other at one end for relative longitudinal movement, means for spreading said arms apart and into shoe-locking position when subjected to said movement, and means for effecting said longitudinal movement to spread said arms and lock them there.
- 20 6. A key for connecting a brake shoe to a brake head, comprising a pair of adjoining overlapping arms slidably connected to each other at one end for relative longitudinal movement, means for spreading said arms apart and into shoe-locking position when subjected to said movement in one direction, and means for effecting said longitudinal movement in both directions and for locking said arms in shoe-locking position.

- 25 7. A key for connecting a brake shoe to a brake head, comprising a pair of adjoining overlapping arms provided at their opposite ends with cooperating tongues and slots permitting one arm to be moved longitudinally of the other, and a latch pivotally mounted on the upper end of said movable arm for effecting said movement and retaining it in selected positions, and means for spreading said arms apart and into shoe-locking 30 position when said movable arm is moved in a predetermined direction.

movement and provided with a lug-engaging detent, said arms also being provided with inter-engaging detents for spreading said arms apart and into shoe-locking position when moved relative to each other, and means for effecting said movement to spread the arms and retain them in that position.

5 8. A key for connecting a brake shoe to a brake head having cooperating lugs, comprising a pair of adjoining overlapping arms extending through 10 said lugs, one of said arms being provided at one end with a slot and the other arm being provided with a tongue slidably disposed in the slot, one of said arms having a lug-engaging detent for locking the key in the lugs when said arms are 15 spread apart, said arms being provided with means for spreading the arms apart when they are moved longitudinally relative to each other, and means for effecting said longitudinal movement and for locking the arms in spread-apart 20 position.

9. A key for connecting a brake shoe to a brake head, comprising a pair of adjoining overlapping arms provided at their opposite ends with cooperating tongues and slots permitting one arm to 25 be moved longitudinally of the other, and a latch pivotally mounted on the upper end of said movable arm for effecting said movement and retaining it in selected positions, and means for spreading said arms apart and into shoe-locking 30 position when said movable arm is moved in a predetermined direction.

FREDERIC SCHAEFER.
